UNITED STATES PATENT OFFICE

WILLIAM R. HULBERT, OF CHICAGO, ILLINOIS

COMBUSTION DEVICE

Application filed October 19, 1931. Serial No. 569,601.

This invention relates to combustion devices according to which heated air and steam are distributed over the bed of fuel in boilers and the like in order to oxidize combustible gases in the fire box and thus generate more heat. In this specification I shall call such boilers, etc., "furnaces."

Various suggestions have been made for supplying both heated air and steam to aid combustion, and the patent granted to McPhee and Krueger, No. 1,827,033 of October 13, 1931, on heat intensifier for boilers shows an air-heating device similar to the one shown herein, with means also for supplying steam.

The chief object is to provide improved means for accomplishing better combustion in such furnaces. Specific objects are to provide simple and advantageous means for conducting live steam to the heat intensifier; to provide an intensifier unit whereby the live steam is advantageously super-heated and directed over the fuel bed; and to provide that a greater quantity of preheated air be so distributed. Other objects and advantages will appear hereinafter.

In the drawing Figure 1 is a side elevation of a fragment of a furnace having a door in closed position and showing pipe means leading thereto.

Fig. 2 is an enlarged vertical medial section through the intensifier unit and the door;

Fig. 3 is a horizontal medial section through the intensifier and door, as on the line 3—3 of Fig. 2;

Fig. 4 is a vertical section through the valve mechanism and an associated pipe; and

Fig. 5 is a fragmentary top view of the door showing the connection of a valve-operating member therewith.

Various advantages of the particular type of bulbous intensifier unit herein illustrated are set forth in said McPhee and Krueger patent, and herein I shall merely describe the structure shown.

The outer and inner bodies 10 and 11 are shown as being substantially spherical, which is the preferred form. The invention in various respects is not limited, however, to the particular shape or type of the intensifier.

These outer and inner bodies are integral through the tubular connecting portions 12 and 13. The structure may be of heat-resisting iron or some other heat-resisting composition moulded or cast a desired shape. These tubular connections provide passageways 6 and 7 respectively into the hollow interior 14 defined by the inner body 11.

There is an integral base 15 secured by bolts 16 to a main support 17 held by bolts 18 upon the furnace door 19. The door is open to the outer air at 20 and the support 17 has an opening 21 leading to the space 22 between the outer and inner bodies 10 and 11, and there is a narrow and elongated nozzle at 23 in communication with the space 22.

According to the construction thus far described, outer air enters and is heated in the space 22 both by reason of the flames or furnace heat playing upon the outer body 10 and by reason of such heat passing through the passageways 7 and 6. Such heated air is discharged at 23 over the fuel bed.

One of the novel features of the present device is in the provision of a tubular member 25, which is shown integral with the inner body 11 but without limitation in that respect, extending from one side of the body 11 diametrically across the other side and being directed toward the discharge opening 23. It is shown as being straight across but it may have other shapes or directions. It has a longitudinal passageway 26, and at what I shall call its outer end there is a discharge nozzle in the form of a plug 27a threaded into an opening coaxial with the passageway 26 and having a small discharge opening 27 directed toward the main discharge opening 23.

At what I shall term the inner end of the tubular member 25 the wall 11 is similarly bored and tapped at 30 to receive the pipe section 31, which by means of several elbows 32 and 33 is placed in communication with a pipe 34, which has connected to it an elbow 35 (Fig. 1) to which is connected a flexible pipe section 36 extending at its other end into the boss 39 of the valve body 40. This pipe

36 is able to hold steam under appropriate pressure.

The valve mechanism shown in Fig. 4 comprises the outer body or casing 40 having a downwardly-extending coaxial integral pin-like support 41. Turning to Fig. 1 we note that the door 42 has hinge lugs 43 coacting with lugs 44 secured to the furnace wall 45 and that there is a hinge pin 46 having a head 46a completing the hinge connection between the furnace wall and the door. This head 46a of the hinge pin is vertically recessed as shown by dotted lines at 47 and into this recess extends the pin or projection 41 of the valve mechanism body.

The valve member 48 is conically tapered and interfits nicely with the inner wall 49 of the body 40. The flange 48a prevents binding of the valve in the body. There is an integral tubular stem 50 issuing from member 48 having a passageway 51 which is continued downward partly through the member 48, and there is a transverse boring at 52 in member 48 reaching to the passageway 51 and providing a port at 53. The boss 39 is bored at 54 to meet the port 53 so that when valve member 48 is in the position shown in Fig. 4 steam may pass through channels 51, 52 and 54 into the hollow interior of pipe 36 and thence to the intensifier.

Turning again to Fig. 1 the tubular valve stem 50 is connected rigidly to a T-coupling 55 into which is threaded a pipe 56. Next follows an automatically-operating condensation discharge device of any well known or approved form; and there is a hand-valve 58 for controlling the passage of steam to the intensifier. The furnace may have several fuel doors and there may be a common pipe line (marked 60 at each broken end thereof shown in Fig. 1) for the several units—one for each door.

The stem 50 and the valve member 48 are sealed by packing 61 and the gland 62.

Since the valve stem 50 is held in a relatively fixed position the valve is operated by turning its body 40. Owing to the general looseness in the door hinge connections 43—44 and the tendency of such doors to sag and have up-and-down movements when opened and closed, it is preferable that means for turning the valve body from the door have some looseness or play at the connection. To this end I provide an arm 65 rigid with body 40 at 66 and extending to a place at the door spaced inward from its hinge connection. This arm 65 may extend to the top edge of the door without resting thereon, as shown in Fig. 1, and therefore the upward and downward movements of the door will not move or put this arm 65 under strain. The arm has a slot 67 (Fig. 5) and a machine bolt 68, threaded into the door through the slot 67 is a driving stud for moving the arm

when the door is swung open and shut. When the door is closed the valve is opened as in Fig. 4, and live steam is discharged at the small nozzle opening 27. When the door is opened the valve is closed, and this enables the fireman to stoke the furnace without the discharge of steam at the furnace door. Since the valve mechanism is mounted on the hinge pin and coaxially therewith the alinement of valve body is maintained. The mechanical construction is peculiarly simple and efficacious. This mechanism as a whole may readily be installed as an attachment device to furnaces already in use.

When steam issues from the small orifice 27 its stream entrains air and causes a greater inflow of outer air into the intensifier unit, thus causing more outer air to reach the fire box above the fuel bed. Owing to the force of the steam jet such air and steam are carried far inward and to the remote portions of the fire box, and there is in general a better diffusion of air and steam over the fuel area.

The advantages of air and steam for aiding combustion are well understood. One of my prime objects is to gain a better distribution of the desired amount of both air and steam in a device of this kind than according to what has been done, so far as I know, hitherto. With this simple device one is able to approximate closely the advantages obtained through much larger and more complicated systems or method for accomplishing the general result.

I contemplate as being included in these improvements all such changes, variations and departures from what is thus specifically illustrated and described as fall within the scope of the appended claims.

I claim:

1. A combustion device of the character described comprising walls forming a hollow bulbous outer body having an intake port and a discharge port substantially at opposite ends of the body respectively and having means for securing the body to a furnace at an air intake opening thereof with such intake opening in communication with said intake port and with said body extending into the fire box of such furnace, there being walls forming an inner hollow bulbous body within and spaced from the walls of the outer body to provide a substantially shallow passageway substantially surrounding the inner body and extending between and opening into said ports respectively, there being at least two tubular devices connecting the interior of said inner body with the exterior of said outer body at widely spaced-apart intervals circumferentially of the outer body for the purpose specified, together with a pipe-like member extending across the interior of said hollow bulbous body and opening at one of its ends adjacent to said discharge port,

with means for conducting live steam to the other end of said pipe-like member.

2. The device of claim 1 hereof in which said bodies, said tubular devices, and said 5 pipe-like member are all integral with each other.

WILLIAM R. HULBERT.
